GAS BURNER WITH UTENSIL SUPPORT

Ervin H. Mueller, Grosse Pointe, Mich.

Application February 16, 1945, Serial No. 578,185

2 Claims. (CL. 126—214)

1

This invention relates to a gas burner construction. The invention is directed particularly to a burner construction which provides a smooth, flat and unobstructed top surface for receiving and supporting cooking utensils.

In accordance with the invention, the burner embodies a body portion which provides ports for the issuance of gas for supporting the flame and a top portion positioned above the body. The top portion extends laterally to provide a surface for supporting cooking utensils and the lateral extent may vary. In some instances, the top portion may extend laterally so as to conceal the underlying body. A plurality of such burners may be employed with a suitable panel or plate so that the entire top of the range is substantially closed and forms a substantially continuous flat or plane surface. The top portion is preferably made so that it is easily removable for access to the underlying structure. The invention embodies the so-called double burner wherein there is an outer flame for general cooking purposes and an inner or smaller flame for simmering purposes. In one form of the invention, the top portion may only cover and cooperate with the inner simmering flame. A further object of the invention is to provide an exposed surface member which is preferably formed of corrosion resisting metal such, for example, as Monel or any one of the various stainless steels or other alloys which remain bright or resist corrosion.

The invention is disclosed by the structure illustrated in the drawings:

Fig. 1 is a top plan view of a portion of a stove or range showing four of the burners of the present invention.

Fig. 2 is an enlarged cross sectional view taken substantially on line 2—2 of Fig. 1.

Fig. 3 is a plan view with some parts cut away and parts shown in dotted lines illustrating the double construction of the burner.

Fig. 4 is a view somewhat similar to Fig. 2 illustrating a still more modified form of the invention.

Fig. 5 is a plan view of the form shown in Fig. 4.

In Fig. 1 the top panel of a range is illustrated at 1 and this may be of suitable metal of sheet form and, insofar as the invention is concerned, it may be rolled steel or a casting, although if it is a casting it is preferred that it be relatively thin as illustrated. This panel is provided with an opening 2 for each burner and preferably the burner top fits nicely in the opening although 55

it is preferred that an adequate clearance be provided as illustrated in Fig. 2. The top surface of each burner is generally illustrated at 3. Of course, the positions of the burners may vary as desired, and the number of the burners employed may likewise vary. A simple arrangement is shown in Fig. 1 which, it is believed, adequately demonstrates the thought.

The burner, illustrated in Fig. 2 and in Fig. 3, 10 is a double type of burner. As illustrated, the burner has a body portion which may be a casting as shown at 5, provided with a hollow interior 6 which forms a channel, while a mixer tube, illustrated largely in dotted lines in Fig. 3 as at 15 7, connects into the channel and has its inlet end arranged to receive the gas jet 9 of a valve or the like. The mixer tube has an opening 10 for primary air which is to be mixed with the gas issuing from the jet 9 and which is controlled 20 by slideable plate valve 11. This control for the primary air is subject to variation in so far as the present invention is concerned.

The burner has also a central part 15 with a 25 hollow interior 16 and connecting into the chamber 16 is a passage or mixer tube 17. The mixer tubes 7 and 17 may be similarly shaped and extend side by side so that the end of the tube 17, as at 18, is positioned adjacent the end of the mixer tube 7 and receives gas from an outlet jet 19. The mixer tube 7 has an opening 20 for primary air and a controlling valve 21. The disposition and location of the free ends of the mixer tubes may be varied and with the arrangement illustrated in Fig. 3, the several valves for controlling the issuance of gas from their jets may be grouped as illustrated in Fig. 1 where the valves are generally shown at 25. Furthermore, each valve may be a double outlet valve which is well known to those versed in the art so that each valve has two jets for the double burner. 30

The outer portion of the burner is completed by a cap 26 which seats upon the two upstanding walls of the outer body 5 and thus closes the chamber 6. The cap may be held in position by 35 any suitable means. The joint at 27 is, of course, tight so that there is no issuance of gas but the part of the cap which seats upon the surface 28 is provided with grooves or channels 29. Thus, each channel 29 provides a port for the issuance 40 of gas therefrom to support the gas flame.

The inner part 15 of the burner has a circumferential top surface 30 for receiving and supporting the top structure of the burner. This top structure includes a body part 31 arranged 45 to substantially fit and rest upon the surface 30

and this part is provided with a grooved or channeled structure as illustrated so that when the same rests upon the surface 30, the channels form outlet ports 32 for the gas which supports the flame. The space 33 between the inner and outer portions provides for secondary air for the inner flame.

The body part 31 is provided with a screw threaded member 35 which may be threaded into the lower portion of the part 15 as illustrated. A laterally extending and load supporting disc-like part 48 may be formed integrally with the body 31. The portion 48 may be made of the material which may be considered unsatisfactory for providing the most desirable exposed surface and, accordingly, may be made of metal cheaper than that desired for the exposed surface. The top or exposed surface, generally represented at 3, is provided by a sheet of metal of disc form, as shown at 41, and this metal which may be of relatively thin stock may, and preferably is of corrosion resisting metal, such as Monel or any one of the several so-called stainless steels or other alloys. The surface sheet 41 may be attached to the underlying support 48 in various ways, but as illustrated in Fig. 2, the sheet has wings or tabs 42 folded over and clamped against the underside of the support 48. As illustrated in Fig. 3, the supporting member 40 may be provided with notches 43 for receiving the wings so that the circular shape of the visible part of the burner is not interrupted. The surface of the member 41 may, if desired, be in a plane which is the same as the plane of the panel 1. However, it is preferred that the surface of the burner be slightly elevated relative to the panel 1, as shown in Fig. 2, and the peripheral edge of the surface member is preferably bevelled as at 45 so that cooking utensils may be moved with sliding action from the panel 1 onto the burner. When the burner is thus slightly elevated any overhanging part of a cooking utensil is out of contact with the panel 1.

Accordingly, it will be observed that the underlying parts of the burner which actually supply the gas for supporting the flame, are concealed from view and that a nice appearing top surface of the range is provided. When the burner is turned on the supporting member 40 and the surface member 41 are, of course, heated and the heat transferred to the cooking utensil resting thereupon. This provides a measure of heat holdover in that when the burner is turned off the top part of the burner may remain hot for a considerable length of time. The burner is of an inexpensive construction in that the parts forming the gas chambers, such as the parts 5 and 15 and the cap 26, are of usual construction. The part 31, however, instead of being an ordinary cap is formed with the concealing overlying disc construction. The assembly is easily made as it is only necessary to insert the screw threaded member 35 and revolve the disc structure until the body 31 moves home onto the seat 39. Likewise, it is very easy to remove the concealing disc structure if it is necessary to have access to any of the underlying parts. It might be pointed out that a suitable ignition system is to be employed for lighting the burners when the gas is turned on but this arrangement is well known to those versed in the art and will be located under the panel 1.

In Figs. 4 and 5 a double burner is illustrated with a top portion which cooperates primarily with an inner or simmering burner. The body

of the burner may be the same as that shown in Fig. 2, and it has the same reference characters applied thereto. The top portion has a part 60 with a laterally extending supporting member 61 preferably provided with a corrosion resisting surface sheet 62. It will be observed that the top portion is relatively small and functions substantially only with respect to the inner or simmering burner. With this type of burner it is preferable to employ a grating structure 63 which overlies the outer or main burner ports so that the heat from the flame of the main burner may have direct access to a cooking vessel of larger diameter than the top portion 61. This grating 63 may, if desired, extend only for a relatively short lateral distance and may be connected to and supported by a panel structure 64. In this form the top of the surface sheet 62 is preferably in substantially the same plane as the top of the grating 63 and panel 64. The purpose of this is so that a large cooking vessel, when placed over the burner, will rest directly upon the surface 62 and at the same time will be supported by the grating 63. It may be desirable to have the surface of the top 62 elevated slightly with respect to the grating 63. When it is desired to use a small cooking vessel or to simmer the contents of a large vessel, such a vessel may rest directly upon the relatively small top portion of the burner and be heated by the inner or simmer flame. In this way the heat is transferred directly through the metal of the portions 61 and 62 to the bottom of the vessel.

35. I claim:

1. A gas burner for use with a gas range having a top panel provided with an opening comprising, a burner body having an outer burner section with outlet ports for flame supporting gas, said burner body having an inner burner section with a wall formation forming a chamber for gas, said chamber being open at its upper end, a top portion, said top portion having a central body part with an edge seating upon the upper edge of said wall formation, one of said edges having alternate projections and grooves which co-operate with the other edge to provide outlet ports for flame supporting gas flowing from said chamber, means for securing the top portion to the burner body, said top portion having an upper part of disc shape extending laterally beyond the burner body and spaced above the body, and the said ports therein, whereby to conceal said outlet ports, said top portion having a flat upper surface lying in a single horizontal plane, the burner body being positioned to support the top portion so that it substantially fits into the opening of said top panel with the upper flat surface thereof lying slightly above said top panel.

2. A gas burner for use with a gas range having a top panel provided with an opening comprising, a burner body having an outer burner section with outlet ports for flame supporting gas, said burner body having an inner burner section with a wall formation forming a chamber for gas, said chamber being open at its upper end, a top portion, said top portion having a central body part with an edge seating upon the upper edge of said wall formation, one of said edges having alternate projections and grooves which co-operate with the other edge to provide outlet ports for flame supporting gas flowing from said chamber, means for securing the top portion to the burner body, said top portion having an upper part of disc shape extending laterally from

the central body part and spaced above the burner body and the outlet ports thereof, said top portion having a flat surface lying in a single horizontal plane, the burner body being positioned to support the top portion so that it lies within the opening in the top panel with its top surface positioned relative to said top panel so that a cooking vessel may rest directly thereon.
